PUSH OPERATOR FOR DOOR LOCK

Norman R. Adler, Fitchburg, Mass., assignor to Independent Lock Company, Fitchburg, Mass., a corporation of Massachusetts

Filed June 29, 1965, Ser. No. 85,945

Term of patent 14 years

(Cl. D50—5)

The dominant features reside in full line portions.
I claim:
The ornamental design for a push operator for a door lock, substantially as shown and described.
